UNITED STATES PATENT OFFICE

EMIL GATHMANN, OF BALTIMORE, MARYLAND

HANGER FOR MOLD TOPS

Application filed May 16, 1931. Serial No. 537,951.

This invention relates to the manufacture of steel ingots of the kind produced in vertical cast iron molds having upper portions or tops made usually of refractory material such as fire clay. The mold top or shrink head casing is ordinarily so supported on the top of a cast iron mold that it may be lowered in the mold after the molten ingot metal has been poured. Heretofore several kinds of devices have been employed for supporting the refractory mold tops on the cast iron molds, the most common practice being to employ blocks or bars which engage lugs or lateral projections on the mold tops and which are removed by the mold attendant when the molten metal reaches the lower portion of the sink head, as shown and described for instance in my United States Patent No. 1,508,931, of September 26, 1924. It has also been proposed to suspend the refractory top in the mold by means of wires or by metal plates projecting laterally from the mold top as shown and described in my United States Patent No. 1,137,264, of April 27, 1915, and it has been further proposed to suspend the refractory top in the molds by means of metal hangers of various kinds which have portions which rest on the top of the cast iron mold and other portions which engage the bottom portion of the refractory top.

My present invention relates to hangers of the last mentioned kind, and it consists in so forming such hangers that, while sufficiently strong to sustain the weight of the mold top during the major part of the mold teeming or pouring operation, they will so weaken during the latter part of such operation that the refractory top will automatically descend and rest or float on the molten metal at the proper time.

In one form of my invention the hanger comprises an upper part adapted to rest on the top of the cast iron mold, a lower part adapted to engage the bottom of the refractory mold top, and an intermediate portion which connects the upper and lower portions, but which, while sufficiently strong to sustain the weight of the mold top during pouring, is more easily softened than the upper and lower portions of the hanger. The arrangement

is such that the softened part of the hanger gives way under the weight of the refractory top and allows the top to descend automatically or to float on the forming ingot at the proper time. 55

In order that my invention may be better understood, reference is made to the accompanying drawings, in which:

Figure 1 is a sectional view of the upper portion of a cast iron mold and a refractory mold top or shrink head casing showing how the mold top is supported on the top of the cast iron mold; 60

Figure 2 is a detail sectional view on an enlarged scale of the construction shown in Figure 1; 65

Figure 3 is a view similar to Figure 1 showing how the mold cavity and mold top or shrink head casing is filled with the ingot-forming metal. This view illustrates how portions of the hangers are severed to allow the mold top to be free from its support on the metal mold and to rest on the forming ingot; 70

Figure 4 is a detail view in section similar to Figure 2 and on an enlarged scale showing how a portion of one of the hangers is severed after being softened by the heat of the molten metal; 75

Figure 5 is a top plan view of the cast iron mold and mold top and the hangers shown in Figure 1; 80

Figure 6 is a perspective view of one of the hangers shown in Figures 1 to 5, inclusive; 85

Figure 7 is a sectional view of the construction shown in Figure 6; and

Figure 8 shows a modified form of hanger. It also embodies the broad features of my invention. 90

In all figures of the drawings, A indicates a portion of a cast iron mold, and B indicates a portion of a mold top or shrink head casing. In Figures 1 to 7, inclusive, H indicates generally the preferred form of mold top hanger. In Figure 8, M indicates a modified form of hanger. The ingot being produced is indicated at I in Figure 3. 95

Hangers made in accordance with my invention must be so constructed that they will 100

be strong enough to support the mold top during the pouring operation, but shall give way at the proper time to allow the mold top either to descend or to float or rest on the top of the forming ingot. The hangers should be so constructed that they may rest upon the top of the cast iron mold, may engage the lower portion of the mold top, and shall have certain portions which will be softened under the heat of the molten metal in such manner that they will break or give way at the proper time. Therefore, I construct each hanger so that it shall have an upper part adapted to rest on the top of an ingot mold, a lower part adapted to engage the lower portion of the mold top, and an intermediate part connecting the upper and lower parts having a portion more easily heat softened than other parts of the hanger, and thus caused to give way or break under the heat of the forming ingot, whereby the mold top is automatically lowered in the mold or is allowed to float or be supported by the forming ingot rather than by the hangers.

In the first six figures of the drawings, I have shown a mold top hanger having an upper part h adapted to rest on the top of the cast iron mold and a lower part h' adapted to engage the lower portion of the mold top. It will be noted that the upper part h is separated from the part h' by a space h^2 . This space is bridged by a metal plate p which is spot-welded to the upper and lower parts. The parts h and h' are preferably made of machine steel bent at x as indicated in Figure 6. The plate P is also preferably made of machine steel but is much thinner than the parts h and h' , so that it may be more easily softened by the heat of the molten metal in the mold.

Figure 1 illustrates how the refractory top is supported by the hangers before the pouring operation commences, and Figure 3 indicates how the plates P are softened and broken when the molten metal rises in the mold. It should be understood that the plates P are arranged vertically, and their tensile strength is entirely sufficient to support the mold top. No lateral or bending strain is exerted on these plates, but the upper and lower parts h and h' are made much thicker because strain is exerted especially at the bends, and therefore it is necessary to make the upper and lower parts especially at the bends, sufficiently strong to support the weight imposed upon them.

In making mold top hangers according to my invention, I preferably employ ordinary machine steel bars sufficiently strong to sustain the weight of the mold top, but so construct these bars that they shall have a portion in their vertical part that is more readily softened by heat than other parts of the hanger. For instance, for a 24" x 24" mold

top weighing 500 lbs., I preferably employ a bar having a thickness of 0.2" and a width of 1.0". The upper and lower parts should have the dimensions just specified in order to sustain, especially at the corners, the weight of the mold top, and/or the impact of the top when inserted in the mold. The vertical portion of the hanger may be made thinner substantially throughout, or it may have a portion which is thinner and which is, say 0.05" thick and 1.0" in breadth. This portion of the vertical part of the hanger will be softened and thus weakened when the molten metal of the forming ingot rises in the mold. For mold tops of other diameters and weights, the breadth and thickness of the hangers may be varied, but there should be a portion in the vertical part of the hanger which readily softens and breaks at the proper time in the manner before explained. The broken upper portions of the hangers may be discarded after the pouring operation. The lower portions of the hangers, if not melted, will adhere to the upper portion of the ingot and may be discarded with the crop.

My improved hangers may be modified in various ways. I have shown only one modification, and this is illustrated in Figure 8, where M indicates the hanger as a whole, the upper part being indicated at m , the lower part at m' , and the vertical part in this instance extends from the bends at m^2-m^2 to the upper and lower parts $m-m'$. The vertical part is made thinner at m^3 , and is therefore more easily softened by heat and more easily broken than other portions of the hanger. This thin portion may be produced in any well known way.

By my invention I have provided a thoroughly practical shrink head casing or mold top support and automatic release, i. e., a mold top hanger or shrink head casing support which is sufficiently strong to sustain the weight of the casing while the mold is being poured, but which, when sufficiently heated, releases the casing to allow it to descend automatically in the mold or to float on the molten metal in the upper part thereof, and thus avoid cracks or tears which would occur if the mold top did not rest upon the forming ingot at the proper time.

It will be observed that in using my invention the mold top or shrink head casing is made somewhat narrower than the upper portion of the mold cavity, leaving a space Y between the casing and the mold in which the hangers are contained. It is a usual practice to leave such space between the mold top and the mold, and therefore my hangers may be employed in connection with ingot molds of the usual kind.

I claim as my invention:

1. A mold top hanger having an upper part adapted to rest on the top of an ingot mold, a lower part adapted to engage the low-

er portion of the mold top, and an intermediate vertical part connecting the upper and lower parts having a vertical portion between the upper and lower parts more easily heat 5 softened than other parts of the hanger, and thus caused to break under the heat of the forming ingot.

2. A mold top hanger for ingot molds having an upper horizontal part, a lower horizontal part, and a vertical part connecting the upper and lower parts, a portion of which between the upper and lower parts is thinner and more easily softened and thus more easily broken than other parts of the hanger for 10 the purpose specified.

3. A mold top hanger for ingot molds having an upper part, a lower part, and a vertical part comprising two members separate from each other but connected to the upper 20 and lower parts and joined to each other by a relatively thin metal bond which is more easily heat softened and thus allowed to break under the weight of the mold top when heated by the molten metal of the forming ingot.

25 In testimony whereof, I have hereunto subscribed my name.

EMIL GATHMANN.
